(57) **CLAIM**

I claim the ornamental design for a wind drive generator for use on an automobile, as shown and described.

DESCRIPTION

FIG. 1 is a front, top and end perspective view of the wind drive generator for use on an automobile embodying the design of the present invention.

FIG. 2 is a top plan view thereof.

FIG. 3 is a bottom view thereof.

FIG. 4 is a front side elevational view thereof, the side opposite to the side shown in FIG. 4 being identical; and,

FIG. 5 is an end elevational view thereof, the end opposite to the end shown in FIG. 5 being identical.
